UNITED STATES PATENT OFFICE.

LE ROY A. CRUMLEY, OF NEW YORK, N. Y., ASSIGNOR TO THE FERRO-ART LIGHTING FIXTURE CO. INC., A CORPORATION OF NEW YORK.

DESIGN FOR A LIGHTING-FIXTURE PART.

Application filed July 17, 1925. Serial No. 14,131. Term of patent 3½ years.

To all whom it may concern:

Be it known that I, LE ROY A. CRUMLEY, a citizen of the United States, and a resident of the county of Bronx, city and State of New York, have invented a new, original, and ornamental Design for Lighting-Fixture Parts, of which the following is a specification, reference being had to the accompanying drawing, forming a part thereof.

In the drawing:

Figure 1 is a front elevational view of the lighting fixture part;

Figure 2 is a top plan view of the lighting fixture part, and

Figure 3 is an end elevation of the lighting fixture part, showing the same in outline.

I claim:

The ornamental design for a lighting fixture part, substantially as shown.

LE ROY A. CRUMLEY.
